Specification for Design.

Patented Mar. 2, 1920.

Application filed June 30, 1919. Serial No. 307,873. Term of patent 14 years.

To all whom it may concern:

Be it known that I, FRED C. POLING, a citizen of the United States, residing at Menlo, in the county of Guthrie and State of Iowa, have invented a new, original, and ornamental Design for a Mud-Lug, of which the following is a specification, reference being had to the accompanying drawing, forming part thereof.

Figures 1, 2 and 3 are a face view, a side elevation and an end elevation, respectively, of a mud lug showing my new design.

I claim:

The ornamental design for a mud lug, as shown.

FRED C. POLING.
